REMOVABLE GLASS HOLDER FOR VEHICLE CHAIR ARMS

Severin B. Hendrickson, Templeton, Mass., assignor to Heywood-Wakefield Company, Gardner, Mass., a corporation of Massachusetts

Application December 2, 1955, Serial No. 39,135

Term of patent 14 years

(Cl. D14—6)

Fig. 1

Fig. 2

Fig. 4

Fig. 1 is a top plan view of a removable glass holder for vehicle chair arms, showing my new design;

Fig. 2 is an end view in rear elevation thereof;

Fig. 3 is a view in side elevation thereof; and

Fig. 4 is a perspective view.

The glass shown in broken lines is disclosed only for purpose of illustration.

I claim:

The ornamental design for a removable glass holder for vehicle chair arms, substantially as shown and described.
